THERMAL RELAY

Murray Ireland, near Elgin, Ill., assignor to
McGraw Electric Company, Chicago, Ill., a cor-
poration of Delaware

Application June 21, 1939, Serial No. 280,284

13 Claims. (Cl. 297—15)

My invention relates to thermal control de-
vices and particularly to snap-acting bimetal
thermostats.

One of the objects of my invention is to pro-
vide a novel snap-acting bimetal thermostat hav-
ing a relatively small temperature differential
of operation.

Another object of my invention is to provide
a snap-acting thermally responsive device in-
cluding at least one compensating portion.

Other objects of my invention will either be
apparent from a description of a preferred form
of my device or will be set forth in detail in the
course of the description thereof.

In the single sheet of drawings,

Figure 1 is a longitudinal vertical sectional
view, of a thermal relay embodying my inven-
tion, taken on the line 1—1 of Fig. 2, showing
the bimetal bar in one limiting position,

Fig. 2 is a top plan view thereof,

Fig. 3 is a side elevational view showing the
bimetal bar in the opposite limiting position,

Fig. 4 is a vertical sectional view taken on the
line 4—4 of Fig. 3,

Fig. 5 is a horizontal sectional view taken on
the line 5—5 of Fig. 3,

Fig. 6 is a top plan view of a modified form
of bimetal bar,

Fig. 7 is a plan view showing another form of
bimetal bar,

Fig. 8 is a cross sectional view taken on the
line 8—8 of Fig. 7,

Fig. 9 is a side elevational view of a bimetal
bar with a heating coil around the end opposite
from that shown in Figs. 1, 2 and 3, and

Fig. 10 is a fragmentary detail view showing a
modified form of bimetal bar and its mounting,
partly in section and partly in side elevation.

The use of a flexible strip of bimetal supported
between rigid or between resilient supporting
means, generally engaging the ends of the strip
to cause the strip to assume a bowed shape, is
already well known. Such devices have the char-
acteristic that the temperature differential of
operation increases with the compression stress
exerted on the strip by the supports, that is, the
greater the amount of initial bowing the greater
will be the temperature change required to cause
the bowed strip to snap across its fixed axis of
pressure.

It is sometimes desirable to reduce this change
of temperature necessary to cause a change of
shape of the initially bowed bimetal strip while
still causing a change of shape to occur with
relatively large power or with relatively vigorous

movement thereof and this may be done by ad-
justable stops engaging the ends of the bowed
strip.

Referring first to Figs. 1 and 2 of the drawing,
I have there illustrated a frame 11 which may
be made of some electric-insulating material, of
substantially L-shape, that includes a main part
13 and a lateral extension 15 thereon, which lat-
eral extension is provided with a lateral notch
or recess 17 in its inner face, which recess is of
substantially V-shape in section. At the other
end of the main part 13 there is mounted a re-
silient bearing member 19 which may be of metal
and of substantially L-shape. As shown in Fig.
15 of the drawing, a lateral portion 20 of member
19 may be secured against the bottom face of
part 13 by one or more screws 21 while the main
part may be adjusted relatively to the part 15,
that is, toward and away from portion 15, by an
adjusting screw 23, the initial shape of member
19 being such that it is bent away from the part
15 of the support 11. In order to prevent turn-
ing movement of member 19 on the end of part
13, a pair of spaced extensions 25 may be pro-
vided between which the main part of member 19
extends upwardly as shown in Figs. 2 and 5 of
the drawing.

A flexible bimetal strip 27, which may be of the
form shown in Fig. 2 of the drawing, is mounted
30 in the frame 11. Bimetal element 27 is prefer-
ably but not necessarily constructed from an in-
itially integral strip having the width shown at
the right-hand portion of the form shown in
Fig. 2, while an L-shaped slot 39 is provided
35 which divides the strip 27 into two parts. One
of these parts is the main portion or leg 31 of
full width for a relatively large part of the length
of the strip and then a narrower or auxiliary or
compensating portion 33 which is narrower than
40 the portion 31. The right-hand end of element
27 is preferably beveled as shown at 35, Fig. 1,
and an aperture 37 is provided in the free or in-
ner end of portion 33.

The beveled end 35 of the main portion 31 fits
45 into the recess 17, of V-shape, in portion 15 of
the supporting frame and the upper end of mem-
ber 19 extends into and through the aperture
37, there being a knife-edge bearing between
member 19 and a wall of the aperture 37. The
50 upper end of member 19 is made narrower than
the other part thereof, to fit into aperture 37.

I provide a pair of adjustable stop members on
the frame 11, each of which is preferably of
metal and include a relatively long shaped bar
55 39 and a shorter shaped bar 41, the lower ends

of each of which are secured to the portion 13 by a plurality of short machine screws 43. Each of these stop members includes an adjustable contact member in the shape of short machine screws numbered respectively 45 and 47. While I have specified that members 45 and 47 are contact members, this is the case only if the device embodying my invention is to be used to control an electrical circuit. If, however, the movement of the main portion is to be utilized in effecting a mechanical movement of an actuated part, these members 45 and 47 may be simple adjustable machine screws. A small electric heater 49 may be supported as by being mounted on the frame 11 in any suitable or desired manner. I have shown this coil as being substantially self-supporting and as being wound around a part only of portion 31 of the main part of the flexible strip. I do not desire, however, to be limited to this position of the auxiliary heating element, the energization of which may be controlled by the movements of the flexible bimetal strip, since this heater may be located in other positions relatively to the thermally responsive strip as will be hereinafter referred to in greater detail.

It will be noted that flexible bimetal strip 27 is unitary and comprises two side-by-side portions, combined to make a member of substantially U-shape, the main and auxiliary or compensating portions being normally coplanar. When the flexible bimetal strip 27 has been mounted in its proper operative position in the two bearings in members 15 and 19, as hereinbefore described, the adjusting screw 23 may be so turned that the flexible support 19 is moved in a clockwise direction (as seen in Fig. 1 of the drawing) whereby a tension stress is placed upon auxiliary portion 33 and a compression stress is placed on the main portion 31. This will result in the portion 31 assuming an arcuate or bowed shape. The less the distance between the two points of the discrete support 11, the greater will be the bowing of the main portion, provided, of course, that the strip is permitted to bow freely. It will be noted that the distance between the supporting points on the discrete support is less than the over-all length of the strip and that the device embodying my invention provides two pivotal bearing supports, one of which is in abutting relation with the bimetal strip and the other of which is in interfitting relation therewith. The axis of pressure of the main portion 31 extends from the bearing in notch 17 to the connection between the adjacent ends of the portions 31 and 33 at the left hand end of element 27, as seen in Fig. 1.

It is, of course, obvious that the greater the amount of bowing of the main portion 31, the greater will be the change in temperature required to cause it to snap across its axis of pressure and that the greater the bowing the greater will be the temperature differential of operation of a device of this kind. However, it may be further pointed out that the compensating portion 33 is effective to reduce this temperature differential of operation because of its action in moving the point of connection of the two portions 31 and 33 in a direction opposite to that in which the main bowed portion tends to move and will finally move, after a predetermined change of temperature. This is because the high temperature component in the flexible bimetal strip is on the same side of both portions. Fig. 3 shows the shape of the flexible strip after it has been subjected to a predetermined change of

temperature sufficient to cause it to move over into an oppositely bowed shape.

As stated above the greater the bowing of the main portion 31, the greater the change of temperature necessary to cause it to move from its initial bowed position to an oppositely bowed position. The auxiliary portion 33 compensates for the effect of this bowing of portion 31 on its operation by reducing the amount of bowing of the main portion 31, since it causes lateral movement of the point of connection of the two portions in a direction opposite to that in which the mid portion of part 31 tends to move in response to temperature changes. It is thus possible to obtain effective snap action of the main portion 31 from one position to another position with relatively small temperature changes acting on the thermostat.

It will be noted further that the axis of pressure is not stationary as in all of the earlier devices of this general kind with which I am familiar, but that it is movable and tilts around the end 35 of the main bimetal portion and that it moves in a direction opposite to the direction of movement of the main portion of the flexible strip 27.

Referring now to Fig. 6, I have there shown a modified form 51 of the main bimetal strip in which a part of the main portion 53 is slightly 30 wider than the adjacent auxiliary or compensating portion 55. This latter portion is longer than the portion 33 of bimetal strip 27. The thermal lag of part 53 will be much greater than the thermal lag of portion 55, hence the compensating action will be relatively large. The greater the length of a bimetal strip, the greater is its response to any given change of temperature, and the auxiliary portion 55 would therefore be more active than would be the case with the auxiliary portion 33 of bimetal strip 27 of Figs. 1 to 5.

Referring now to Figs. 7 and 8 of the drawing, I have there shown a built-up thermal element 57 comprising a relatively heavy and long main bimetal portion 59 and an auxiliary or compensating portion 61 shorter than the main portion and also thinner. These two strips have an end of each in side-by-side adjacent positions, which ends are connected by a cross bar 63 and rivets or other suitable securing or holding means. In all other respects this element 57 operates in exactly the same manner as was hereinbefore set forth for bimetal element 27. The main portion 59 being relatively heavy will respond to any change of temperature more slowly than will a thinner or narrower strip such as is shown for strip 61. If, therefore, it is desired to provide a thermal relay for a device to be controlled thereby, which device has a relatively large thermal mass and therefore reaches its maximum operating temperature relatively slowly, the main bimetal portion 59 or 31 will be made relatively large, either in width or in thickness or in combination. If quick and more active compensation is desired, the compensating portion 61 or the compensating portion 33 will be made of much smaller mass per unit of length or long, as in portion 55, relative to the main portion. If, on the other hand, a device having but small thermal mass is to be controlled by a thermally responsive device of the kind shown in the drawing, the main portion can be made to have relatively small mass, as by using a thin main portion, and where for any reason relatively sluggish compensation is desired, the compensat-

ing portion 31 or 33 may be made of relatively greater unit mass and shorter.

Referring to Fig. 10 of the drawing a support 13 may have a metal bar 65 secured thereto by screws 67, the bar 65 having a notch 69 therein to provide a knife-edge bearing in an aperture 71 in the end portion 73 of bimetal bar 75. The main bar 75 is substantially the same as main bars 31, 53 and 59 and has an auxiliary or compensating portion connected therewith as in the other modifications already referred to. The end portion 73 thus overhangs the support 65 and may be used to control and actuate electrical or mechanical devices not shown.

I may also use a single main bar 31 and two auxiliary compensating bars 33 to form a thermostat of flattened C-shape, in which case the construction of Fig. 10 would be used, the support 65 then engaging the second compensating bar instead of the main bar, the thermal relay then having an increased sensitivity and a reduced temperature differential of operation.

I have found it possible also to vary the compensating action by the location of the auxiliary heating element 49 which can be connected in series circuit with the thermal relay to have its energization controlled thereby in a manner well known in the art. Thus when the heating element 49 is positioned near that end of the flexible bimetal strip remote from the connected end of the compensating strip, as shown in Figs. 1, 2 and 3, the compensating strip will be heated mainly by heat conducted from the far end of the main portion through the length of the main portion and from there across the bridge connecting the end of the main portion with the adjacent end of the compensating portion. Thus if a device of this kind be used as a thermal timer to control a plurality of closely succeeding repetitive cycles of operation, as in automatic toasters, it may be desirable or necessary to provide definite degrees of compression of the main portion or compensating effect of the auxiliary portion to adapt the thermal relay to the time temperature curve of the different devices with which it may be associated.

As an example of definite positions of the heating element 49, it may be moved farther toward the compensating portion of the bimetal strip or it may even be located around the left-hand end of strip 21, as shown in Fig. 9, in which case heat radiated therefrom will affect not only the main portion but also simultaneously the auxiliary portion 33, whereby an early compensating effect may be obtained in the operation of the thermal device.

This latter construction, that is the one where the auxiliary and the narrow part of the main portion of the bimetal strip are simultaneously subjected to change of temperature, will be of value in those cases where it is desired to obtain a relatively small temperature differential of operation of a thermal relay of the kind herein disclosed.

It is obvious that my improved thermostat can also be operated by a reduction in temperature instead of an increase in temperature and that the use of an auxiliary heating means or of an auxiliary cooling means is optional and that the thermostat may be made to operate to control heat or cold by being subjected solely to the temperature of the ambient air or of a mass or member, the temperature of which is to be controlled.

While I have illustrated and described several forms of device embodying my invention, I do

not desire to be limited thereto as further modifications may be made and all such modifications coming within the scope of the appended claims are to be considered as part of my invention.

5 I claim as my invention:

1. A snap-acting bimetal thermostat comprising a main part having a predetermined length and a shorter compensating part having one end secured to one end of said main part and extending toward the other end of the main part and discrete supporting means engaging the other end portions of said main and compensating parts and applying stresses of different character thereto which result in a bowed shape of the main part.

10 2. A snap-acting bimetal thermostat comprising a relatively long main part and an integral shorter compensating part normally coplanar with each other and of substantially U-shape and supporting means having a length less than that of the main part and engaging the free ends of the main and the compensating parts to apply compression to the main part and tension to the compensating part, said compressive stress causing a bowing of the main part to one side of the axis of pressure of the main part, change of temperature causing a quick movement of the main part across said axis of pressure.

15 3. A snap-acting bimetal thermostat comprising unitary main and auxiliary portions normally coplanar and partially coextensive with each other and supporting means having one part thereof in interfitting relationship with one of said portions and causing abutting relationship 20 of the other portion with another part of the support, the distance between the two parts of the supporting means being less than the length of the main portion by substantially the length of the auxiliary portion.

25 4. A snap-acting thermo-responsive device comprising a flexible strip of bimetallic material divided into two connected parts by an L-shaped slot therein and bearings pressing oppositely on the respective parts, at least one of said bearings 30 being pivotal, acting to initially bow one of said parts, a change of temperature causing said bowed part to move across the axis of pressure into an oppositely bowed position.

35 5. A snap-acting thermo-responsive controlling device comprising a flexible strip of bimetallic material divided into two connected parts by an L-shaped slot therein and a pair of spaced supports respectively pivotally engaging an end portion of the parts of said strip to initially compressively stress and bow one part of said strip and to tension the other part of the strip.

40 6. A thermo-responsive device comprising a pair of pressure-exerting bearings and a flexible strip of bimetallic material having an L-shaped slot therein to divide the strip into two partially coextensive connected parts, the free ends of the parts of said strip being pivotally supported by said bearings whereby one of said parts is stressed in tension and the other of said parts is stressed in compression and initially bowed and is operative to move with a snap-action across a movable axis of pressure into an oppositely bowed position.

45 7. A snap-acting thermo-responsive controlling device comprising a flexible strip of bimetallic material having an L-shaped slot therein to divide the strip into two partially co-extensive connected parts and a two point supporting means for said strip having knife-edge connections with the free end portions of the respective

parts of the strip, the strip being so mounted that the supporting means exerts a tension stress on one of said parts and a compression stress on the other of said parts causing it to bow and to snap from one bowed position to an oppositely bowed position across a movable axis of pressure in response to changes of temperature, said axis of pressure tilting in a direction opposite to that of the movement of the snap-acting part.

8. A snap-acting bimetal thermostat comprising a main and a shorter auxiliary portion normally in coplanar positions with adjacent ends secured together and discrete supporting means having two thermostat-supporting bearings pivotally engaging the respective portions at points spaced a shorter distance apart than the length of the main portion with the connected ends of the two portions positioned at one side of the axis of pressure of the supporting means, said supporting means applying an adjustable compressive stress to the main portion to cause it to assume an arcuate shape at one side of a floating axis of pressure and move to the other side of said axis of pressure with a quick action on being subjected to a predetermined change of temperature.

9. A snap-acting thermally responsive device comprising a flexible main bimetal bar and means for supporting it in initially bowed position including a flexible auxiliary bimetal bar integral with the main bar at one end and partially coextensive therewith and two pivotal bearings engaging respectively the free end portion of the main bar and the free end portion of the auxiliary bar to subject the main bar to an initial longitudinal compression stress, said main bar being thereby bowed and moving across the axis of pressure with a snap-action on change of temperature, said axis of pressure tilting in an opposite lateral direction relatively to the direction of movement of the main bar around the point of engagement of the main bar with its bearing.

10. A snap-acting thermosensitive device comprising a flexible bimetal member of substantially U-shape having normally coplanar legs of unequal length and means including the shorter leg for supporting the longer leg at two spaced points in initially longitudinally compressed condition to cause it to assume a bowed shape, change of temperature causing said longer leg to move across an axis of pressure passing through said two supporting points, which axis of pressure turns in a direction opposite to that of the movement of said longer leg.

11. A snap-acting thermo-responsive device comprising a flexible bimetal strip having a main part and at least one compensating part normally coplanar with each other in flat side-by-side and partially coextensive positions and discrete supporting means engaging the strip at two points a lesser distance apart than the length of the main part, said supporting means applying an adjustable compressive stress to the main part to cause it to assume an arcuate shape at one side of a floating axis of pressure passing through the two points of support and to move across said axis of pressure with a sudden action on being subjected to a predetermined change of temperature.

12. A snap-acting thermo-responsive device comprising a flexible bimetal strip including a main part and at least one compensating part normally coplanar with each other in flat side-by-side and partially coextensive positions and an adjustable support for the strip engaging the same at two points spaced apart a distance less than the length of the main portion, said supporting means applying a tension stress to the compensating part and a compressive stress to the main part to cause the main part to assume a bowed shape at one side of an axis of pressure passing through the two points of support and to move across said axis of pressure with a quick action on predetermined change of temperature, said axis of pressure moving laterally in a direction opposite to the direction of movement of the main part and simultaneously therewith.

13. A snap-acting thermo-responsive device comprising a flexible metal strip having a main part and two compensating parts, the respective outer ends of the compensating parts being connected to the ends of the main part to cause the compensating parts to be partially coextensive with the main part and to have their inner ends extend toward each other at one side of and normally coplanar with the main part and discrete supporting means engaging the inner end portions of the compensating parts to apply tension stresses to the compensating parts and a compression stress to the main part to cause the main part to bow to one side of an axis of pressure passing through the two points of support and to move across said axis of pressure with a snap action on predetermined change of temperature, said axis of pressure moving laterally simultaneously in a direction opposite to the direction of movement of the main part.
